UNITED STATES PATENT OFFICE.

GEORGE W. NEWTON, OF NEWTON, IOWA, ASSIGNOR TO W. P. JOHNSON, OF DES MOINES, IOWA.

TOY GUN.

1,211,870.

Specification of Letters Patent.

Patented Jan. 9, 1917.

Application filed January 11, 1916. Serial No. 71,445.

To all whom it may concern:

Be it known that I, GEORGE W. NEWTON, a citizen of the United States, and resident of Newton, in the county of Jasper and State 5 of Iowa, have invented a certain new and useful Toy Gun, of which the following is a specification.

The object of my invention is to provide a toy gun of the pistol type having a bell 10 received within the shell of the gun preferably in its chamber and similar to the ordinary cylinder chamber of a revolver or pistol, and having a hammer and trigger and suitable mechanism of comparatively simple 15 construction, whereby the hammer will ordinarily be held away from engagement with the bell, which parts are so arranged that by pulling the trigger the hammer may be first raised and then subjected to the action of 20 a spring, whereby it is made to strike the bell and then moved away from contact with the bell.

A further object is to provide such a gun with simple and inexpensive means for 25 mounting the movable parts, whereby the cost of the manufacture may be held at the minimum.

My invention consists in the construction, arrangement and combination of the various 30 parts of the device, whereby the objects contemplated are attained as hereinafter more fully set forth, pointed out in my claims and illustrated in the accompanying drawings, in which:

35 Figure 1 shows a side elevation of a toy gun embodying my invention. Fig. 2 shows a central, vertical, longitudinal, sectional view, through the same. Fig. 3 shows a similar view of a part of a gun with the 40 movable parts in their positions assumed at the end of the pull on the trigger, and Fig. 4 shows a sectional view taken on the line 4-4 of Fig. 2.

45 My improved gun comprises a hollow shell made in two opposite halves each comprising a cylinder portion indicated in the accompanying drawings by the references numeral 10, a barrel portion 11 and a socket or butt portion 12. The halves may be secured together by means of rivets or the like extending through opposite projecting flanges 13.

50 Mounted within the cylinder chamber 10 of the gun is a gong bell 14, which will again 55 be referred to. The movable parts of a

gun are preferably assembled and mounted before being placed within the gun shell, upon a plate 15 having a portion received within the upper part of the stock, as clearly shown in Figs. 2 and 4, and a portion extending forwardly in the gun adjacent to the inner side of the cylinder chamber 10, as shown in Fig. 4. By so assembling the parts of the plate such assembled parts may all be mounted on the gun stock and cylinder at once. A hammer 16 is pivoted at its lower end to the central portion of that part of the plate 15 which is received in the stock of the gun. A portion of the hammer projects upwardly through a suitable opening in the upper part of the stock. The hammer 16 has a forwardly projecting lug 17 for striking the bell 14.

55 Pivoted below the hammer 16 on the lower part of the plate 15 is a trigger 18, having a portion projecting downwardly through a suitable opening in the stock of the gun. The upper end of the trigger 18 is spaced slightly below the lower end of the hammer 16, and has an upwardly 60 projecting lug 19.

65 Formed on the lower portion of the hammer 16 is a forwardly projecting portion 20 to which is pivoted a plate 21 which extends downwardly beyond the hammer 16, and has at its lower rearward portion a laterally extending flange 22 adapted to be engaged by the lug 19 in certain position of the movement of the trigger 18. The plate 21 extends upwardly beyond the portion 20 and has at its upper end a laterally extending lug 23 extending in the opposite direction from the direction of extension of the flange 22 and away from the hammer 16, as 70 shown in Fig. 2.

75 Approximately at the central forward portion of the hammer 16 is a laterally extending lug 24 arranged to stand in the path of the lug 23 during the rearward movement of said lug 23, as hereinafter described. Near the rear lower part of the hammer 16 is a laterally extending lug 25. At the rear end of the plate 15 is a laterally extending lug 26.

80 Mounted on the lug 26 is a coil spring 27, one end of which extends upwardly and forwardly in the gun at 28, and thence downwardly and forwardly at 29. The lower end of the portion 29 is pivoted to the trigger 18 rearwardly of the pivotal point of such 85

trigger, and is adapted to hold the trigger normally in its forward position, as shown by the full lines in Fig. 2. The other end 30 of the spring coil 27 extends forwardly 5 and upwardly, in the gun spaced from the portion 28 and engages the lower edges of the lugs 25 and 23, as clearly shown in Fig. 2. The forward end of the portion 30 also engages the lower edge of the lug 24. 10 The spring, the hammer and the portion 21 are so arranged that the spring normally holds the hammer with the portion 17 slightly spaced from the bell by the engagement of the spring portion 30 with the lugs 15 25 and 24 and also by its engagement with the lug 23, whereby the lug 23 is normally held in engagement with the lug 24.

The parts having been assembled on the plate 15, said plate is placed in one-half of 20 the bell gun shell, and is secured thereto by means of a rivet 31, whereby the bell, the plate, and one-half of the gun shell are secured together, as shown in Fig. 4. The plate 15 is also preferably made, so that it 25 fits against the shell of the gun at its upper and lower edges, so that it is held firmly against movement. The parts having been assembled in the half of the bell gun shell, the other half is assembled in position and 30 secured to the half in which the parts are mounted.

I will now describe the operation of the movable parts. When the lower part of the trigger 18 is drawn rearwardly to the position shown by dotted lines in Fig. 2, the lug 35 19 engages the flange 22 of the plate 21, thereby forcing the lower part of the plate forwardly and moving the plate on its pivotal point for causing the lug 23 to engage 40 the lug 24 and force the hammer rearwardly against the pressure of the spring portion 30 on the lug 25. When the trigger has been pulled far enough so that the lug 19 clears the flange 22, the upward pressure of the 45 spring 30 against the lug 25 will swing the hammer sharply forwardly, whereby the portion 17 is caused to swing past its normal position and strike the bell 14. The spring then moves rearwardly to its normal 50 position. In operating the gun it will be

seen that it is unnecessary to touch the hammer, the gun being entirely operated by the movement of the trigger and the action of the spring.

It will be seen that the parts are of comparatively simple construction, so that most all of them can be stamped out with dies and prints, so that they can be made at a minimum cost. The movable parts are assembled on the plate 15, which can be done 60 much more easily than could be done if they were secured directly to the gun shell. The plate is then installed in the gun by one fastening means, namely the rivet 31, and the gun shell halves are fastened together, 65 whereupon the device is complete.

The parts when made of suitable metal are very durable, so that the gun is comparatively long lived.

It will be understood that some changes 70 may be made in the construction and arrangement of the parts of my improved toy gun without departing from its essential features and purposes, and it is my intention to cover by this application any such changes 75 which may be included within the scope of my claims.

I claim as my invention:

1. In a toy gun, a shell, a bell in said shell, a plate adapted to fit within the shell 80 and be secured thereto, and an operative mechanism for striking said bell mounted on said plate.

2. In a toy gun, a shell, a plate adapted to fit within said shell, a bell, means for securing said bell to said plate and to the wall of said shell, and an operative mechanism mounted on said plate for striking said bell. 85

3. In a toy gun, a hollow shell made in parts adapted to be secured to each other, a plate adapted to be mounted within said hollow shell, a bell, means for securing said bell to said plate and to the wall of said shell, and operative mechanism mounted on said plate adapted to strike and ring said bell, having a part projecting through said shell. 90 95

Des Moines, Iowa, October 28, 1915.

GEO. W. NEWTON.
